TYPE-WRITING MACHINE.

1,221,126.

Specification of Letters Patent.

Patented Apr. 3, 1917.

Application filed December 2, 1914. Serial No. 875,103.

To all whom it may concern:

Be it known that I, CLIO B. YAW, citizen of the United States, and resident of Arlington, in the county of Hudson and State of New Jersey, have invented certain new and useful Improvements in Type-Writing Machines, of which the following is a specification.

My present invention relates to line spacing mechanism for typewriting machines and its principal object is to provide new and improved mechanism of the character specified.

To the above and other ends my invention consists in the features of construction, combinations of devices and arrangements of parts hereinafter described and particularly pointed out in the claims.

In the accompanying drawings illustrating the preferred form of my invention,

Figure 1 is a fragmentary plan view partly in horizontal section showing the platen of a typewriting machine embodying my invention.

Fig. 2 is an end elevation viewed from the left showing the platen carriage and line spacing mechanism for the platen, the platen itself being removed.

Fig. 3 is a vertical sectional view taken on a plane indicated by the dotted line α in Fig. 2 and looking in the direction of the arrow at said line.

Fig. 4 is a fragmentary plan view showing the right-hand end portion of the platen.

Fig. 5 is a perspective view of the line spacing pawl or dog and its mounting.

Fig. 6 is a fragmentary detail view showing the line spacing pawl in arrested position after operation.

Fig. 7 is an enlarged sectional detail view showing the detent devices for the line space adjuster or regulator.

As appears from Fig. 2 a stationary guide rail 1 grooved at its top and bottom to receive anti-friction balls 2 coöperates through said balls with the slide bar 3 of a carriage which further includes end bars fixed to said slide bar, the right-hand end bar 4 being shown. Pivotedly connected at 5 to the end bar 4 is a lug 6^a projecting from a cap or housing 6 comprised in a platen frame which further includes cross rods 7 and 7^a detachably fixed to said cap. The cross rod 7 is connected through pairs of links 8 and

9, (the right-hand pair only being shown) with angular plates 10 fixed to the slide bar 3. The parts or links 8 and 9 are included in mechanism for moving the platen and its frame on the carriage or truck comprising the slide bar 3 with which mechanism the present invention is not specifically concerned. In addition to the cap 6 and cross rod 7 the platen frame further comprises a left-hand end portion 11 which provides a bearing for the left-hand section or portion 12 of the platen shaft or axle, the right-hand section or portion whereof is indicated by the numeral 13. The platen 14 is provided at its left-hand end with an ordinary platen head 15 which bears a fixed relationship with the section or stub shaft 12. At the right-hand end of the platen is arranged a line spacing ratchet wheel 16 provided with peripheral teeth 17 and crown teeth 18. The ratchet wheel is housed within the cap 6 and is operatively connected with the platen preferably by clutch devices corresponding with those found in the Remington No. 10 typewriting machine but not shown herein. By pressing in the usual finger piece 19 secured to the axle 13 said axle may be moved inward endwise to render said clutch devices inoperative and disconnect the platen from its ratchet wheel. Coöperative with the teeth 17 at the under side of the ratchet wheel is a detent roller 20 mounted on a spring arm 21 which is screwed or otherwise secured to the cross bar 7, the roll coöperating with the teeth 17 through a slot 22 cut in the under side of the cap 6. The shaft 13 bears in an opening bored through the hub portion 6^b of the cap 6 and also bears in a flanged bushing 23 which, as clearly appears in Fig. 3, is threaded into the inner face of the cap 6 and is rigid with said cap. For conveniently detaching and attaching the bushing the outer face of its flange or head 24 is provided with a nick or slot 25 to receive a screw driver. The bushing forms, in effect, an inner hub for the cap and provides a bearing for a dog or pawl carrier designated as a whole by the reference numeral 26, as best shown in Fig. 5. The pawl carrier bears rotatably on the bushing 23 so that it is mounted co-axially with the platen and is provided at its outer or free end with a radial slot 27 forming two separated arms between which is arranged an

actuating device or pawl 28 pivoted on a pin 29 which bridges the slot. A spring 30 confined between the pawl and the bottom of the slot 27 tends constantly to turn the 5 pawl or actuating member 28 on its pivot 29 and throw the upper end of the pawl into engagement with the teeth 18. A stop pin 31 projecting from the side of the pawl above its pivot contacts with the face of the 10 carrier to limit this movement of the pawl. The upper end of the pawl is approximately lozenge-shaped being beveled at opposite sides as indicated at 32 and 33, thereby providing at the inner side of the pawl a tooth 15 34 for coöperation with the teeth 18. Connected to a lug 35 extending downward from the carrier 26 is the forward end of a draw spring 36 which at its rear end is anchored to a lateral pin 37 on the housing 6. This spring tends constantly to 20 throw the upper portion of the pawl carrier forward about its pivot and normally maintains the pawl carrier in engagement with a stop pin 38 projecting laterally inward from the inner face of the housing. In order to turn the pawl carrier to effect line space movements, means are provided comprising a series of beveled teeth 39 formed on a coned part or member 40 which 25 is rigid with the pawl carrier 26 and may be formed integrally therewith but for convenience of manufacture is preferably made separate and then is suitably fixed to the outer face of the pawl carrier. When thus manufactured the hub of the piece 40 may 30 be forced into an opening in the carrier 26 and provide in effect a bearing or bushing for the carrier as will be understood from Fig. 3. The teeth 39 form in effect a mutilated beveled pinion and this beveled pinion 35 constantly meshes with a small mutilated beveled gear 41 which is pivoted on a headed shoulder screw 42 that takes into the under side of the hub 6^b, said gear projecting inward through an opening 43 in the vertical 40 wall of the housing 6. The gear 41 is provided with a hub 44 over which is fitted an arm or lever 45, said arm being secured to the under side of the beveled gear by one 45 or more screws 46. The arm 45 curves forward under the platen axle and its forward end is bent or curved slightly toward the left and is provided with an upstanding finger piece or handle 47. When this finger 50 piece is pushed toward the right it turns the gear 41 in the direction of the arrow (Fig. 1) the gear acting through the pinion 39 to turn the pawl carrier and pawl rearward. Normally the pawl 28 is held up 55 out of engagement with the ratchet wheel 16 by adjustable devices so that the platen is normally disconnected from the pawl and may be turned by the finger wheels 19 without interference from said pawl. These 60 adjustable devices comprise a curved plate, 65

pawl stop or regulator 48 which slidably fits over the upper cylindrical portion of the housing 6 and is provided with tongue-like projections 49 and 50. The projection 49 is at the front side of the plate 48 and coöperates with a slot or guide opening 51 formed in the rod 7^a while the projection or tongue 50 extends from the rear of the plate 48 and coöperates with a slot or guide opening 52 formed in the rod 7. A finger piece 53 projects upward from the regulator or stop plate 48 and affords a convenient means of sliding the same backward and forward. The finger piece is bored out as indicated at 54 to receive a coiled spring 55 that presses downward a ball detent 56 and tends to maintain said ball in engagement with one or another of three depressions or seats 57 formed in the curved face of the housing 6. The detent devices 56, 57 maintain the plate 48 set in one or another of three predetermined positions corresponding with the three different extents of line space movement. The variation in the line space movement is 70 brought about by means of a slot or opening 75 formed in the plate 48 and comprising a narrow fore and aft portion 58 and a wider portion 59 connecting with the rear end of the portion 58. This slot overlies a larger cut-out or opening 60 formed in the housing 6. The slot 58, 59 coöperates with a headed pin or projection 61 which is supported on the top of the pawl 28 and projects upward through the opening 60 into the slot 58, 59. Normally the pawl is in the narrow portion 58 of the slot, its position lengthwise thereof being determined by the adjustment of the plate 48. It will be understood that the inner wall of the portion 58 coöperates with the pin 61 to resist the spring 30, the result being that the pawl is normally held upright and the tooth 34 is out of engagement with the ratchet teeth 18. When the finger piece 47 is operated, causing the carrier 26 to swing toward the rear, the pin 61 will travel backward through the narrow portion of the slot 58 until the wide portion 59 is reached, permitting the spring 30 to become effective and swing the pawl 28 toward the left with the result that the tooth 34 is caused to engage with the ratchet teeth 18 and during the remainder of the rearward swing of the pawl carrier will co-operate with said teeth to turn the ratchet wheel 16 and through it the platen 14. It will be understood that the extent of this turning movement will depend on the point in the stroke at which the pawl engages with the ratchet wheel and that this point is determined by the adjustment of the plate 48. When the plate is in the forward one of its three positions, the rear portion of the narrow slot 58 will be engaged with 80 85 90 95 100 105 110 115 120 125 130

the pin 61 and said pin will have to travel a comparatively short distance before it enters the wide portion 59 of the slot, permitting the pawl to become operative. The parts are adjusted so that when the plate 5 is thus set three units of line space distance will be communicated to the platen from the pawl and ratchet mechanism. When the plate 48 is set in its rearmost 10 position as determined by the detent devices comprising the ball 56 and the rearmost depression 57, the pin 61 will have to traverse the greater part of the slot 58 before it enters the slot 59 with the result that but a single unit of line space movement will be given the platen. When the plate 48 is set in the middle position two 15 units of line space movement will be communicated to the platen by the pawl and ratchet devices. Preferably a cover plate 20 62 is secured over the plate 48 by screws 63, thus covering the slot 58, 59 and pin 61. To facilitate the proper adjustments of the line spacing devices, indicating devices are 25 provided comprising a pointer 64 formed by beveling or sharpening the forward end of the tongue 49. The pointer 64 coöperates with suitable indicating marks or a scale on an indicator plate 65 screwed to the housing 6. In order that the pointer 30 may slide over said plate 65 which projects outward from the face of the housing, the forward portion of the finger 49 is undercut as indicated at 66 (Fig. 2). To limit 35 the stroke of the pawl and ratchet devices a stop lug 67 is formed or suitably secured to the inner face of the housing 6, said lug being provided with suitable faces 68 and 69 for coöperation respectively with the 40 rear upper portion of the carrier 26 and the beveled portion 33 of the pawl. These stop faces or stop devices may, of course, be made separate, if desired. The operation 45 of the stop devices will be best understood from a consideration of Fig. 6 which shows the pawl in coöperation with the stop 67. The stop, it will be understood, serves not only to positively limit by its face 68 a rearward movement of the carrier, but also 50 through its face 69 exerts a wedging action on the pawl, forcing it into a locking engagement with the engaged tooth 18 of the ratchet wheel 16 at the end of the pawl stroke. The variation in line space movement 55 is effected without varying the movement of the pawl and ratchet line spacing devices or the finger piece 47, the stroke or movement being always uniform or constant, the variation in the effective stroke 60 of the pawl being caused by varying the point in its full or constant stroke at which it may engage with the line spacing ratchet wheel.

The present construction of the line 65 spacing mechanism is simple and effective

and possesses the advantage of being contained within and covered by a housing at one end of the platen, which housing is of substantially the diameter of the platen, this construction conducing to a neat and 70 attractive appearance of the parts and also covering the working parts so that their liability to become displaced or disarranged is minimized. The housing provides a support for the pawl carrier and pawl as well 75 as for the operating arm or lever 45 and the connections between said arm and the pawl carrier, said connections comprising the gears 39 and 41. This support being detachable, the entire line spacing mechanism 80 excepting the ratchet wheel may be quickly removed from the machine.

Various changes may be made without departing from my invention.

What I claim as new and desire to secure 85 by Letters Patent, is:—

1. In a typewriting machine, the combination of a platen, a ratchet wheel connected thereto, a hand-actuated pawl-carrier having separated arms, a pawl mounted between 90 said arms and having one end lozenge-shaped so that one beveled portion formed thereby may coöperate with said ratchet wheel, and a fixed stop with which another beveled portion of said lozenge-shaped end may co- 95 operate.

2. In a typewriting machine, the combination of a rotary platen, a line spacing ratchet wheel connected therewith, a pawl carrier mounted co-axially with said ratchet wheel, 100 a pawl pivoted on said carrier at right angles to the carrier axis, hand actuated means for communicating an unvarying extent of rotary movement to said pawl carrier, spring means tending constantly to press said pawl 105 toward said ratchet wheel, and adjustable means for varying the point in the stroke at which said spring means becomes effective, said adjustable means comprising a settable slotted plate and a projection on said pawl 110 engaging said plate.

3. In a typewriting machine, the combination of a rotary platen, a line spacing ratchet wheel connected therewith, a cylindrical housing at one end of the platen and 115 containing said ratchet wheel, a pawl carrier, a pawl thereon, means for actuating said pawl, and a pawl regulator mounted on said housing, said pawl carrier and said pawl being contained within said housing. 120

4. In a typewriting machine, the combination of a platen frame, a rotary platen, a line spacing ratchet wheel connected therewith, a cylindrical cap detachably mounted on said platen frame, a pawl carrier, a pawl thereon, a hand lever, and connections between said hand lever and said pawl carrier, said pawl carrier, said hand lever and said connections being mounted on said cap. 125

5. In a typewriting machine, the combina-

tion of a platen frame, a rotary platen, a line spacing ratchet wheel connected therewith, a cylindrical housing detachably mounted on said platen frame, a pawl carrier, a pawl thereon, a hand lever, and connections between said hand lever and said pawl carrier, said pawl carrier, said hand lever and said connections being mounted on said housing, and said pawl carrier and said pawl being 10 contained within said housing.

6. In a typewriting machine, the combination of a platen frame, a rotary platen, a line spacing ratchet wheel connected therewith, a cylindrical cap detachably mounted

on said platen frame, a pawl carrier, a pawl 15 thereon, a hand lever, and connections comprising a pair of constantly meshing gears between said hand lever and said pawl carrier, said pawl carrier, said gears and said hand lever being mounted on said cap. 20

Signed at the borough of Manhattan, city of New York, in the county of New York, and State of New York, this 1st day of December, A. D. 1914.

CLIO B. YAW.
